FASTENER

Daniel A. Brennan, deceased, late of Chicago, Ill.,
by Elmer L. Zwickel, executor, Chicago, Ill., as-
signor to Acco Products, Inc., Long Island City,
N. Y., a corporation of New York

Original application December 16, 1940, Serial No.
370,372. Divided and this application July 22,
1942, Serial No. 451,844

3 Claims. (Cl. 24—153)

This application is a division carved out of applicant's co-pending application Serial No. 370,372, filed Dec. 16, 1940.

The invention relates broadly to a paper fastener of the type embodying a compressor and a base, the latter having spaced prongs adapted to be bent over a face of a stack of loose sheets for binding them together; and more particularly to a fastener including a resiliently flexible compressor.

Paper fasteners previously proposed all have been subjected to numerous disadvantages. For example, certain types of fasteners have stiff compressors provided with sliding latches which hold the prongs bent thereover, but which, in certain instances of use, are highly objectionable. Other known types of fasteners have rigid compressors suitably formed at their ends to coact with the prongs to hold them bent. None of the known types of compressors embody means to effect a clamping or wedging action on the stack of sheets so as to securely bind them under tension at least at the prongs.

It is, therefore, an object of the present invention to provide a paper fastener compressor of a type which effectively co-acts with the prongs and the stack of sheets being bound to tightly bind said sheets in place.

Another object of the invention is to provide a resilient paper fastener compressor of the type adapted to have prongs associated therewith which is easy to assemble in place on a stack of sheets, simple to operate, positive in operation, and inexpensive to manufacture.

Another object is to provide a novel paper fastener including a resiliently flexible compressor characterized by the entire absence of movable parts and which adequately serves to cover the associated prongs from being inadvertently engaged by adjacent files or other objects.

The foregoing and such other objects of the invention as will appear hereinafter as the description proceeds, will be more readily understood from a perusal of the following specification, reference being had to the accompanying drawing; in which:

Fig. 1 is a perspective view showing the improved fastener applied to a stack of loose sheets.

Fig. 2 is a longitudinal elevational view of the fastener, partly broken away, showing the stack of sheets in section.

Fig. 3 is a view similar to Fig. 2, showing the compressor partially disengaged from the base element.

Referring particularly to the drawing, the fastener illustrated includes a base 11 provided at its ends with bendable resilient prongs 12 adapted to be placed in cooperative position with a stack of sheets 13 for holding them together in a file. The base 11 normally has its intermediate body portion positioned to lie flat against the bottom of the stack of sheets with the spaced prongs 12 extending through similarly spaced holes 14 therein. The free end portions of the prongs extend through and beyond the top of the stack. A compressor 15 is adapted, when properly mounted, to overlie the free end portions of the prongs and prevent said prongs from catching on adjacent files or the like.

The compressor 15 preferably is formed of an elongated strip of thin resiliently flexible material such as, for example, spring steel, press-board plastics, or the like, and is of a length substantially equal to the spacing between the prongs 12. The strip 15 is bent downwardly at each end and then outwardly and upwardly to provide smooth, rolled, depending bearing portions 16 at each end for a purpose to be explained hereinafter.

The downwardly extending portion of the strip is suitably apertured or otherwise slotted transversely, as at 17, to receive the free end portions of the prongs 12 when the compressor is in place.

To assemble the fastener, one of the slotted openings 17 is slid over one of the extending prong portions, as best shown in Fig. 3, and then the compressor is deflected or bowed longitudinally to engage the other prong in the opposite opening 17. Release of the pressure utilized to deflect the compressor will cause it to move into its normally straight position. During this movement its ends slide along the associated prongs 12 until the bearing portions 16 of the compressor abut the vertical prong portions at their bends. While in this position, the bearing portions 16 engage the top sheet of stack 13 adjacent to the prongs and the resiliency of the compressor will bind the prongs to the compressor and sheets. It should be observed that movement of the compressor, from the bowed position illustrated in Fig. 3 into its final position shown in Fig. 2, results in co-action between the bearing portion 16, prongs 12, and the stack of sheets 13. This is occasioned by engagement of the free edges of the bearing portions 16 with the bottom faces of the now bent over prong portions, thus tending to wedge the prongs upwardly relative to the top face of the stack. This action obviously tends to compress the sheets tightly together at the

openings 14 thus binding them securely, at the prongs, between said bearing portions and the intermediate body portion of the base 11.

The compressor may be removed simply by grasping it substantially midway between its ends and lifting upwardly, which operation will draw the slotted ends of said compressor off of the underlying prong portion.

Although an exemplary form of fastener has been illustrated in the accompanying drawing and described in detail in the foregoing specification, it is obvious that the invention may readily incorporate other features than those specifically disclosed and may vary in arrangement and use without departing from the spirit of the invention and scope of the appended claims.

What is claimed is:

1. A compressor for a paper fastener of the type including a base having prongs adapted to be passed through holes in a file of papers and subsequently bent over toward the top face of the file, said compressor comprising a flat strip of resiliently flexible material to overlie the prongs having a rolled bearing portion at each end offset below the plane of the strip and engaged beneath the bottom face of the complementary prong at its bend to retain the compressor in place and tightly bind the papers at the prongs.

2. A compressor for a paper fastener of the

type including a base having spaced prongs adapted to be passed through holes in a file of papers and subsequently bent down inwardly towards each other, said compressor comprising a flat strip of material to overlie the prongs, said strip having slots one adjacent each end to receive the respective prongs threaded downwardly therethrough with the prongs overlying the respective end portions, said end portions being offset downwardly and rolled outwardly and then upwardly to define semi-cylindrical bearing portions arranged to slide freely over the top of the file of papers and wedge beneath the respective prongs at their bends.

3. A compressor for a paper fastener of the type including a base having spaced prongs adapted to be passed through holes in a file of papers and subsequently bent down inwardly towards each other, said compressor comprising a flat strip of material having its end portions turned downwardly, each down-turned end portion having a prong receiving opening closely adjacent to its juncture with the intermediate body portion of the strip, and the portion between said opening and its free edge being rolled outwardly longitudinally and then upwardly to dispose its edge in the plane of the bottom edge of said slot.
